UNITED STATES PATENT OFFICE.

SOLOMON P. BAUGHMAN, OF HERRING, OHIO.

CLEVIS.

SPECIFICATION forming part of Letters Patent No. 239,700, dated April 5, 1881.

Application filed December 10, 1880. (No model.)

To all whom it may concern:

Be it known that I, SOLOMON P. BAUGHMAN, of Herring, in the county of Allen and State of Ohio, have invented a new and Improved Plow-Clevis, of which the following is a specification.

The object of this invention is to provide a simple device for regulating the depth of the furrow made by the plow.

10 Figure 1 is a side elevation of a section of a plow-beam with the device in position thereon. Fig. 2 is a plan of the same, and Fig. 3 is a side elevation of a modification of the device. Similar letters of reference indicate corresponding parts.

In the drawings, A represents a plow-beam.

B is a metal strap passing over the end and upper and lower faces of the beam A, to strengthen the same.

20 C is the clevis, swiveled on the pin a, that passes laterally through the plow-beam A, and said clevis C has an ear, b, projecting upward from each side thereof, above the upper face of the beam A, and between these ears b b is swiveled a plate, D, having a central screw-thread, as indicated at d, through which plate D the adjusting screw-rod G is passed.

In the rear of the clevis C a bolt, E, having a screw-threaded hole, f, made through its head, 30 is passed down through the strap B and beam A, and secured in position by the nut g on its end, the head h of said bolt E projecting above the upper face of the beam A, and having passed horizontally through it the rod H, that is designed to extend to the plow-handle, within easy reach of the operator. In rear of the bolt E an eyebolt, F, for supporting the rear prolongation of the rod H, is passed down through beam A and secured in place by a nut, k.

40 A short rod, G, provided with a left-hand screw-thread and with an eye, m, is passed

from the rear through the hole d of the swiveled plate D, and a longer rod, H, provided with a right-hand screw-thread and with a hook, n, is passed through the hole f of the bolt E, and connected by means of its hook n with the eye m of the rod G. This rod H is prolonged rearward through the eye of the eye-bolt F, and has a crank, o, on its rear end.

By turning these rods H G by means of the 50 crank o the clevis C is elevated or depressed, as the case may be, so that as the plow is drawn along the line of draft is raised or lowered, and the furrow thereby made more shallow or deep.

55 In Fig. 3 a modification of this device is shown, in which the clevis C, instead of being swiveled upon the plow-beam, as shown in Figs. 1 and 2, is hinged or jointed on both sides, as shown at p, to the lugs N, that are firmly 60 bolted on either side of the plow-beam A, so that said clevis C is free to move in a vertical plane. Said clevis C is in all other respects the same as that shown in Figs. 1 and 2.

I am aware that it is not new to raise or 65 lower a draft-link plate by means of an angled lever on the beam connecting by a link with a hand-lever; also, that it is not new to combine a wheel, worm-shaft, rack, and pinion to raise or lower a clevis; but

70 What I claim is—
The combination, with a clevis, C, pivoted at a and having the ears b b, of the plate D, swiveled in said ears and centrally threaded, the loosely-jointed and reversely-threaded 75 bolts G E, the fixed nut f, the guide F, and the crank o, rigidly connected with bolt E, as shown and described.

SOLOMON PERRY BAUGHMAN.
